UNITED STATES PATENT OFFICE

163,125

CARD PUNCH

George H. Kress, Vestal, N. Y., assignor to International Business Machines Corporation, New York, N. Y., a corporation of New York

Application November 23, 1949, Serial No. 6,234

Term of patent 14 years

(Cl. D64—11)

To all whom it may concern:

Be it known that I, George H. Kress, a citizen of the United States of America, residing at Vestal, in the county of Broome and State of New York, have invented a new, original, and ornamental Design for a Card Punch, of which the following is a specification, reference being had to the accompanying drawings, forming part thereof.

Fig. 1 is a perspective view of a card punch embodying my new design.

Fig. 2 is a side elevation of the same as seen from the right end.

Fig. 3 is a rear elevation of the same.

I claim:

The ornamental design for a card punch, as shown.

GEORGE H. KRESS.
